Assistant Examiner — Kaitlan Walker

(57) CLAIM

The ornamental design for a hanging decoration, as shown and described.

DESCRIPTION

FIG. 1 is a front, top perspective view of a hanging decoration, showing my new design;

FIG. 2 is another front, top perspective view of the hanging decoration;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of detail "9" identified in FIG. 1. The dash dot dash broken lines in FIGS. 1 and 9 depict the boundary of the enlargement of the hanging decoration and form no part of the claimed design.

1 Claim, 9 Drawing Sheets
